Primary Examiner — John A Voytek(74) *Attorney, Agent, or Firm* — Schwabe, Williamson & Wyatt, P.C.(57) **CLAIM**

The ornamental design for a tire as shown and described.

DESCRIPTION

FIG. 1 is a front perspective view of a tire, showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines show features of the tire that form no part of the claimed design.

1 Claim, 6 Drawing Sheets---
